CALCULATING MACHINE

Eugen Benninger, Zurich, Switzerland

Application February 15, 1935, Serial No. 6,752
In Switzerland and Germany February 26,
1934

1 Claim. (Cl. 235—60)

The present invention relates to an improved calculating machine and more especially to calculating machines of the type in which selecting pins are slidably arranged in consecutive rows on a movable carrier, the said pins being adapted to be set by a plurality of numeral keys and which said selecting pins when set allow the carrier to advance one step or a plurality of steps. The principal object of the invention is to provide an improved construction of the means to set the selecting pins.

With this and incidental objects in view, the invention consists in certain novel features of construction and combinations of parts, the essential elements of which are set forth in appended claim, and a preferred form of embodiment of which is hereinafter described with reference to the drawings which accompany and form part of the specification.

In the drawings only the novel devices are shown and of all the elements of the calculating machine only those are diagrammatically illustrated which are necessary for the understanding of the invention.

On the drawings:

Fig. 1 shows in a plan view the carriage with the selecting pins and some keys and the means to stop the carriage;

Fig. 2 is a top view of the lever to stop the carriage and means to release, displace said stop temporarily;

Fig. 3 shows the stop lever-releasing pin in side elevation seen in the direction of arrow A;

Fig. 4 illustrates in side elevation part of the carriage the parts being shown as seen in the direction of arrow B of Fig. 1;

Fig. 5 shows the stem of a selecting pin and a spring to retain same in its position;

Figs. 6, 7 and 8 are side elevations of parts of the keys and the selecting pins and of the carrier illustrating the co-operation of the said parts;

Fig. 9 is a side elevation of a part of the calculating machine to which the improvements are applied, the parts being shown in a diagrammatical manner.

In the drawings 10 denotes a carriage or carrier of selecting pins of known construction. The carrier 10 comprises two plates 11, 12 (Figs. 1, 4, 5, 6, 7 and 8) arranged parallel to each other and rigidly connected with each other. In holes of the plates 11, 12 selecting pins 13 are slidably arranged in parallel rows denoted 0-9. The elements 13 are movable in the direction of the arrows D (Fig. 4). The elements of the rows 1

to 9 are of substantially rectangular cross-section. The stem of each pin 13 of the row marked 0 is provided with a lug 18 (Fig. 5). Between the adjacent sides of two selecting pins 13 there is arranged a U-shaped blade spring 15 which rests on the lower plate 12. One shank 16 of the blade spring 15 presses against a projection 14 of a pin 13, the other shank which is provided with guiding laps 17 embraces the adjacent pins 13. The springs 15 are designed to retain the selecting pins in their positions.

A coiled spring 19 interconnects the carrier 10 and the frame of the calculating machine. The spring 19 (Fig. 1) tends to draw the carrier in the direction of the arrows E (Fig. 1). The carrier 10 is slidably mounted on guides in the frame of the machine in the well known manner (not shown in the drawings).

On a bolt 20 of the machine frame a double armed lever 21 is rotatably mounted. To one arm of the lever 21 a coiled spring 22 is attached which tends to draw the said arm against a fixed abutment 23. To the other arm of the lever 21 a pawl 24 is pivotally connected. The pawl 24 rests against the lug 18 of the first selecting pin 13 of the row "0". A spring 26 attached to the said pawl 24 and to the frame of the machine tends to hold the nose 25 in the locking position, shown in Fig. 1. Above the plate 11 of the carrier 10 and running parallel thereto a shifting rod 27 is arranged which is connected to two arms 28, 29 pivotally mounted in the frame of the machine, by means of the shaft 30.

31, 32 and 33 (Figs. 1, 6, 7, 8) denote three numeral keys marked 0, 00 and 000 respectively which are slidably mounted in the frame of the calculating machine. The keys 31, 32 and 33 are movable each against the action of a spring 49 (Fig. 9) in the direction of the arrows F (Figs. 6-8). The key 31 is provided with an arm 34 (Figs. 1 and 6) having a downwardly projecting foot 35 (Fig. 6). The foot 35 is positioned in the plane G—G in which all the selecting pins 13 of the 0-row are arranged. The dimension b of the foot 35 is equal to the dimension b' of a selecting pin 13. The key 32 is provided with a foot 36 (Fig. 7). The dimension b'' of the foot 36 exceeds slightly the distance b³ of two consecutive lugs 18. The foot 36 of the key 32 is positioned outside the plane G—G, but well within the reach of the lugs 18 of the selecting pins 13 of the 0-row. The arm 37 interconnects the foot 36 with the corresponding key. The dimension b⁴ of the foot 36 of the key 33 is about twice the distance b³ of two consecutive lugs 18. The 55

- foot 38 is outside the plane G—G but still above the lugs 18 of the selecting pins 13 of the 0-row. The foot 38 is connected to the key 33 by an arm 39. Each of the arms 34, 37, 39 of the keys 31, 32, 33 is provided with an extension 40 which rests on the rod 27. A spring not shown in the drawings keeps the rod 27 in contact with the extensions 40; the keys are held thereby in their raised position.
- 10 The pawl 24 is operated by an angular lever 41 pivotally mounted on a stud 42 of the frame of the machine (Figs. 2 and 3). An arm 43 of the lever 41 projects into the path of the rod 27. The other arm 44 abuts on the free end of the pawl 24.
- 15 The device works as follows:
- By depressing the numeral key 31 the foot 36 (Fig. 6) strikes against the selecting pin 13 and presses the same downwardly in the carrier 20 frame 11, 12 until the upper end 13' is flush with the upper face of the plate 11. The projection 14 (Fig. 5) forces the shank 16 of the blade spring 15 backward, the latter again secures the pin 13 in its lowermost position. The selecting 25 pin 13 in this position projects in the path 45 of a slide 47 which is guided in the frame of the calculating machine, and which is moved in the direction of the arrow 46 (Fig. 1). The said slide 47 is provided with a rack 48 which operates 30 a toothed gearing as described below. While the selecting pin 13 below the foot 35 is pressed downwardly the key 31 presses the rod 27 downwards by means of its extension 40 (Fig. 6), in the direction of the arrow H (Fig. 3). The 35 angular lever 41 is moved in the direction of the arrow J and its arm 44 strikes against the free end of the pawl 24 in the direction of the arrow K (Fig. 2). The tooth 25 (Fig. 1) of the pawl 24 is brought out of contact with the lug 18 of 40 the selecting pin 13 nearest to the pawl 24. The carrier frame 10, by the action of the spring 19, is now drawn in the direction of the arrow E (Fig. 1) until the next following selecting member 13 (Fig. 6) strikes with its face 13'' against 45 the foot 35 which is still in its depressed position. If now key 31 is released it will be raised by the spring 49 (Fig. 9) and thereupon the rod 27 will be returned to its original position by a spring (not shown). The pawl 24 is re- 50 turned by the spring 26 until it is again in the path of the lugs 18 of the selecting pin 13 of the 0-row. The pins which have been previously displaced are of such dimensions that the tooth 25 is returned into the path of the lug 18, before 55 the foot 35 is out of engagement with the face 13'' (Fig. 6) of the selecting pin 13. If therefore the foot 35 proceeds in its upward movement the selecting pin 13 is set free after the pawl 24 has resumed its initial position. The 60 carrier 10 being free to follow the spring 19 (Fig. 1) slides in the direction of the arrow E until the lug 18 of the foremost selecting pin 13 strikes against the tooth 25 of the pawl 24. The carrier 10 is arrested thereby. When the lug 18 65 strikes against the tooth 25 the pawl 24 takes up the stroke and swings out against the action of the spring 22. The latter cushions the stroke and returns the pawl 24 when the carrier 10 assumes its correct final position and is ready for 70 being operated again by striking another or even the same numeral key. The carrier 10 performs its movements very quickly and there is no need to insert a pause between the striking of the keys, the latter may be operated in very quick 75 succession.

In case where in place of one selecting pin 13 of the 0-row two are to be simultaneously pressed down, the key 32 is depressed. By striking the key 32 the foot 36 is being moved downwardly and it comes to strike against the two 5 lugs 18 (Fig. 7) of two consecutive selecting pins 13. If the downward movement of the key is being proceeded with the selecting pins 13 are pushed downwardly until the foot 36 strikes against the plate 11. Simultaneously the tooth 10 25 of the pawl 24 has been brought out of engagement with the lug 18 of the selecting pin in such a manner that the carrier 10 is moved under the action of the spring 19 in the direction of the arrow E (Fig. 1). The carrier 10 15 comes to rest as soon as the nearest selecting pin 13a (Fig. 7) strikes with its lug 18 against the foot 36 of the key 32. When released the key 32, by the action of spring 49, returns to its initial position (Fig. 7). As soon as the foot 36 20 comes out of engagement with the lug 18 the carrier 10 moves again under the action of the spring 19. It moves in the direction of the arrow E (Fig. 1) until the lug 18 of the selecting pin 13a strikes against the tooth 25 of the 25 pawl 24. The carrier 10 is therefore being moved for a distance which is equal to the distance between two consecutive selecting pins 13.

To operate three selecting pins 13 of the 0-row at the same time the key 33 is used which works 30 similarly to key 32. Only the dimensions are different and there are always three pins moved instead of only two.

It is evident that not only three but also four or more selecting pins may be moved at the same 35 time.

The machine comprises one slide 47 for each row of selecting pins 13. To each slide 47 one end of a coiled spring 59 is attached, the other end being connected to the frame of the machine. 40 The slides 47 are held in their in-operative position against the action of spring 59 by means of a hand lever 50, link 60, lever 61 and rod 51. To the hand lever 50 the one end of a spring 63 is connected, the other end being fixed to the frame 45 of the machine. By moving the lever 50 against the action of the spring 63 in the direction of the arrow (Fig. 9) the slide 47 is permitted to be moved by spring 59. The slide 47 is withdrawn by the spring 59 in the direction of arrow 52 until 50 the nose 45 strikes against the pin 13 which previously has been set. The slide 47 rotates by means of the rack 48 the toothed gear 55 of a counting or adding device which may be of any known construction. Moreover a spur wheel 53 is rotated 55 which operates a printing device 54.

The number keys 1 to 9 are provided with the usual extensions corresponding to the extensions 40 of the keys 31—32—33, and these usual extensions 40 operate on the rod 27 in the same manner 60 as the keys 31—32—33. That is to say, whenever a number key 1 to 9 is depressed it will depress the bar 27 and cause actuation of the pawl 24 so that the pawl 24 will release the stop 18 adjacent to it and permit the box of pins to move one-half 65 step until the next pin 13 strikes the foot of the key exactly as if the "0" key, 31, had been depressed. When the respective number key then again rises, the foot of that key releases the number pin 13 so that the box of pins can advance 70 through the second half of the step. At the same time the rod 27 rises and releases the pawl 24 so that this pawl, upon the next half step of the box of pins, again drops into position in front of the next stop 18 and again arrests the box of pins.

It is therefore unnecessary to depress the "0" key 31, upon depression of any of the number keys 1 to 9 in order to release the box of pins.

It is principally for pin carriage escapement under control of numeral keys other than zero keys 31-33 that pawl 24 is swung by bail 27. When the carriage is escaped by keys 31-33 pins 13 of the zero row are depressed flush with plate 11 so that swinging of pawl 24 in the direction 10 of arrow K is not essential.

While the form of mechanism herein shown and described is admirably adapted to fulfill the objects primarily stated, it is to be understood that it is not intended to confine the invention to 15 the one form of embodiment herein shown and described, as it is susceptible of embodiment in various forms, all coming within the scope of the claim which follows.

What is claimed is:—

20 In a calculating machine, a pin carriage having rows of selecting pins from "0" to "9", a set of pin setting keys from "0" to "9", means continuously tending to advance said carriage in one direction,

an escapement for effecting a release of said carriage for step by step movement, a shifting rod common to all of said setting keys, connections between said shifting rod and said escapement whereby upon depression of a key for setting a 5 selecting pin corresponding thereto the escapement will be operated to allow a single step actuation of said carriage; in combination with an auxiliary key cooperating with said shifting rod and the zero row of said selecting pins and including means to set a predetermined number greater than one of said selecting pins of said last named row and effecting said escapement to permit said carriage to advance a distance equal to the number of step-distances corresponding to 15 the number of selecting pins set by said auxiliary key, said selecting pins which are controlled by said auxiliary key having lugs and said auxiliary key having a foot to engage the lugs of the predetermined number of selecting pins and be itself 20 engaged by the lug of the next succeeding pin as a stop.

EUGEN BENNINGER.
